UNITED STATES PATENT OFFICE.

HARUKICHI TOMIZAWA, OF TOKYO-FUKA, JAPAN, ASSIGNOR TO ALFRED HAGUE AND COMPANY, INC., OF NEW YORK, N. Y., A CORPORATION OF NEW YORK.

PYROTECHNIC DEVICE.

Application filed July 29, 1927. Serial No. 209,226.

This invention relates in general to pyrotechnic devices, and, more particularly, to a harmless combined sparkler and explosive.

According to the invention, a pyrotechnic device is provided which may consist essentially of a body made of a material which, when ignited, will emit a profusion of harmless sparks, similar to the usual sparkler used for amusement and other purposes. The body may also have incorporated therein a substance which, preferably after the sparkler material has burned itself out, will explode giving a harmless and mild explosion accompanied by a quite loud report.

The device according to the invention, may be made up of a shell or tube of combustible material, such as paper, the paper preferably being initially in the form of a long strip which is rolled into a helix to form a tube having closed ends. The upper end of the tube may be adapted to be lighted by a match, and the tube may hold, for a comparatively large part of its length, the usual sparkler compound which may be in the form of a powder. The lower end of the tube may be tightly twisted to form a more or less solid paper handle. Preferably at the lower end of the sparkler powder and near the handle explosive powder may be provided to give the mild and harmless explosion and report. The paper may be appropriately colored, and the handle may have a distinct coloration so that the proper end will be lighted.

Among the features of the invention is the provision of a harmless pyrotechnic device which will give the consecutive effects of a sparkler and explosive. Furthermore, the provision of a combustible body or support for the sparkler and explosive material eliminates the dangers due to the relatively heavy non-combustible rod found in the usual sparkler.

Various other features and advantages of the invention will be apparent from the following particular description and from an inspection of the accompanying drawings.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, the mode of its

operation and the manner of its organization may be better understood by referring to the following description taken in connection with the accompanying drawings forming a part thereof, in which

Fig. 1, is an enlarged section in elevation of the device according to the invention, the middle part being broken away and parts exaggerated to better illustrate the unique construction; and

Fig. 2, is an outside elevation of the device.

Fig. 3, is a section on the line 3—3 of Fig. 1.

Fig. 4, is a section on the line 4—4 of Fig. 1.

In the following description and in the claims parts will be identified by specific names for convenience, but they are intended to be as generic in their application to similar parts as the art will permit.

Like reference characters denote like parts in the several figures of the drawings.

Referring now to the drawing, the device, as illustrated, comprises a body of paper, the body being made from a straight strip 1, of relatively light tissue paper rolled into a helix in the manner shown. The upper part of the body may be made in the form of a hollow tube 2. The lower part of the body may be tightly twisted to form a more or less solid paper rod to act as a handle 3 for the device. The paper strip 1 is wound helically with the adjoining convolutions overlapping to provide the necessary strength and to make a powder tight tube. The paper strip may be suitably folded and then twisted in a helix at the upper end to effectively close the top of the tube 2 to prevent loss of the contents, this being shown in Fig. 3.

If desired, the paper may be suitably decorated to have an attractive appearance. The paper strip may be provided with a colored edge extending the length of the paper strip so that a helical colored line will be formed when the paper is twisted to form the body. The handle 3 of the body may be colored with a distinctive color so that it will be easily recognized to insure the proper end being lighted.

Throughout the major extent of the hollow tube 2, a suitable sparkler powder 4 may be placed. This sparkler powder may be any of the powders normally used to give the usual sparkler effect. The luminous effect of the burning sparkler material is well known, the material causing a profusion of harmless sparks shooting in all directions

over a limited range, giving a luminous and pleasing effect.

At the lower end of the hollow tube 2 a comparatively small amount of explosive powder 5 may be placed so that, after the sparkle powder is burned out, the explosive powder will be ignited. This explosive powder is of such a nature that it will burn very quickly, giving a mild explosion and causing 10 a fairly loud report.

To use the sparkler, the handle 3 will be held in the hand and the upper end ignited by a suitable source of fire. The sparkler powder will immediately begin to burn providing its characteristic effect, the paper tube burning along with the sparkler powder. When the sparkler powder burns down to the explosive powder, a mild and harmless explosion causing a sharp report, occurs. In 20 some cases, it may be preferable to hold the device with the handle end up during the burning thereof.

The device is harmless, the sparkler composition giving off non-burning sparks and the paper burning completely and leaving an ash which does not hold heat. There is no core of non-combustible material to get hot and burn the careless users, which are mostly children, during and after burning of 30 the device. The explosion is mild, and merely enough to give a sharp crack or report, and not enough to cause even a slight injury. The device is absolutely safe and, by the combination of the sparkler and fire-cracker effect, makes a very attractive and pleasing amusement device.

The burning of the sparkler powder gives the usual pleasing effect and the culmination of the sparkler effect with a mild explosion 40 is unique and unusual and adds greatly to the attractiveness of the device from an amusement standpoint. Furthermore, due to the construction and use of harmless materials, there is nothing to harm the careless user. 45 Also due to the great simplicity and efficiency of construction, the device may be made quite inexpensively and yet to give uniform satisfaction.

50 Although certain novel features of the invention have been shown and described and are pointed out in the annexed claims, it will be understood that various omissions, substitutions and changes in the several steps

of the process and in its operation and in the form and details of the apparatus illustrated may be made by those skilled in the art without departing from the spirit of the invention.

What is claimed is:

1. A pyro-technic amusement device comprising a body made up of a strip of thin paper wound helically to form an upper hollow tube and also to form a substantially tight lower handle, a small amount of explosive powder in the lower part of said tube, a 60 relatively large amount of sparkler powder extending from the upper end of said tube to said explosive powder, the upper end of said tube being suitably closed to prevent escape of said sparkler powder, said paper and 65 sparkler powder burning together completely and gradually down to said explosive powder emitting a shower of harmless sparks as they burn and leaving a quick-cooling harmless ash. 75

2. A pyro-technic device comprising a rod-like body, sparkler material incorporated with said body at the upper portion and extending a substantial part of the length of said body, a relatively small amount of explosive material below and adjoining said sparkler material and also incorporated with said body, the lower end of said body forming a handle, said upper portion burning completely and gradually down to said explosive material, emitting a shower of harmless sparks as it burns and leaving a harmless residue. 85

3. A harmless combined sparkler and explosive comprising a tube of combustible material which will leave a quick cooling ash, sparkler material and pyro-technic material disposed within said tube, said tube and sparkler material burning together and gradually, emitting a profusion of harmless sparks as they burn. 90

4. A sparkler comprising a tube of combustible material which will leave a quick-cooling harmless ash, sparkler material within said tube, said tube and sparkler material burning together and gradually, emitting a profusion of harmless sparks as they burn. 100

In testimony whereof I have hereunto set my hand and seal.
